United States Patent Office

Des. 219,195

Patented Nov. 10, 1970

219,195

TIRE

Richard J. Skerl, Barberton, Ohio, assignor to The B. F. Goodrich Company, New York, N.Y., a corporation of New York

Filed Nov. 21, 1969, Ser. No. 20,208

Term of patent 14 years

Int. Cl. D12—14

U.S. Cl. D90—20

The figure is a perspective view of a tire showing my new design.

It is to be understood that the tread pattern continues as shown throughout the circumference of the tire, and the tread shoulder on the side opposite the portion shown is a mirror image thereof.

The characteristic features of the design reside in the tread and tread shoulder portions of the tire.

I claim:

The ornamental design for a tire, substantially as shown and described.
